United States Patent Office.

S. BALDWIN CHAPMAN, OF NEW YORK, N. Y.

Letters Patent No. 75,521, dated March 17, 1868.

IMPROVED CAR-WHEEL.

The Schedule referred to in these Letters Patent and making part of the same.

TO ALL WHOM IT MAY CONCERN:

Be it known that I, S. BALDWIN CHAPMAN, of the city, county, and State of New York, have invented a new and improved Car-Wheel; and I do hereby declare that the following is a full, clear, and exact description thereof, which will enable others skilled in the art to make and use the same, reference being had to the accompanying drawings, forming part of this specification.

This invention relates to a new and improved wheel for railway-cars, and it consists in a novel and improved manner of constructing the wheel, as hereinafter fully shown and described, whereby several advantages are obtained over the ordinary cast-iron wheel, to wit: first, the avoidance of breakage and the consequent accidents arising therefrom, an entire cast-iron wheel being very liable to crack; second, a diminution of the wear and tear of the rails and rolling-stock, the latter not being subjected to the jars and concussions which they receive when on the ordinary cast-iron wheels; third, greater durability and economy, the length of time my improvement will last or run, rendering them far less expensive than the ones now in use. In the accompanying drawings—

Figure 1 is a side sectional view of my invention, taken in the line $x-x$, fig. 2.

Figure 2, a vertical section of the same, taken in the line $y-y$, fig. 1.

Similar letters of reference indicate corresponding parts.

My improved wheel is constructed of iron and wood, with an elastic material for the inner ends of the wood portions to rest or bear upon.

A represents a cast-iron circular plate, provided with a flange, α , at one side near its periphery, and cast with a hub, B, which projects horizontally from the side opposite to that which is provided with the flange α , (see fig. 2.) C represents sections of wood, which are of taper form, the sides being radial with the wheel, (see fig. 1,) and the grain of the wood also being radial with the wheel, so that the exterior surfaces of the sections C, which form the "tread" of the wheel, will be endwise of the grain. This insures great durability. The sections should be constructed of some hard, durable wood, such, for instance, as hickory or oak, and adjusted snugly to the wheel, their inner ends resting against an elastic ring, A $\times$, of India rubber or other suitable elastic substance, which is fitted on the hub B, the thickness of the sections being equal to the length of the hub B, as shown in fig. 2. The sections have an annular concentric groove in each side of them, to receive metal rings D D, and a bolt, b, passes through each section C, and through the plate A, and a plate, E, which may be of wrought or cast-iron, and fitted against the sides of the sections opposite to the sides against which the plate A is fitted. By screwing up the bolts b, the sections are firmly clamped between the two plates A E. Besides these bolts b, the plate E is secured by others, c, which pass into the end of the hub B. The edge or periphery of the plate E is flush with the exterior of the wooden sections C, but the plate A is sufficiently great in diameter to project beyond the exterior surface of the wood sections to form the flange of the wheel.

The wheel thus constructed is very strong and durable, and may be made at a reasonable cost, and will run without transmitting jars or concussions to the cars, the wood sections C, in connection with the elastic ring A $\times$, insuring this result; the holes in the sections C, through which the bolts b pass, being made sufficiently large to admit of the yielding or giving of the sections to a necessary degree.

Having described my invention, I claim as new, and desire to secure by Letters Patent—

A wheel for railway-cars, composed of the metal plates A E, wooden sections C, and the elastic ring A $\times$, all being secured together by bolts, and used with or without rings D D, substantially as herein shown and described.

Witnesses:

W.M. DEAN OVERELL,

J. A. SERVICE.

S. BALDWIN CHAPMAN.
